UNITED STATES PATENT OFFICE.

ALFRED L. ECCLES, OF TRENTON, NEW JERSEY, ASSIGNOR TO JOHN MADDOCK, OF TRENTON, NEW JERSEY.

SAD-IRON.

No. 894,943.

Specification of Letters Patent.

Patented Aug. 4, 1908.

Application filed July 3, 1906. Serial No. 324,674.

To all whom it may concern:

Be it known that I, ALFRED L. ECCLES, a citizen of the United States, residing at Trenton, in the county of Mercer, in the 5 State of New Jersey, have invented certain new and useful Improvements in Sad-Irons, of which the following is a specification.

My invention relates to internally heated sad irons, and to that kind thereof which are 10 heated by gas, and is intended to be applicable to all sizes of such sad irons, be the same reversible or non-reversible.

The object of my invention is to produce an efficient sad iron capable of being heated 15 to a high degree by a properly directed and regulable flame in which perfect combustion of the gas is effected, and which is so screened as to obviate all injury to the fabrics upon which the iron may be used.

20 Heretofore great difficulty has been experienced in efficiently heating a single faced iron without auxiliary apparatus for forcing commingled gas and air through the burner within the combustion chamber of the iron.

25 All efforts of this kind, so far as I am aware, have resulted unsatisfactorily owing to failure to procure a perfect combustion of the gas used and such force in the flame as to direct it satisfactorily against the inner face of 30 the bottom of the iron.

In the accompanying drawings I have shown my invention applied to a sad iron having a single face, and have illustrated means whereby I secure a strong flame having 35 a short light blue inner heat cone having a blowing or explosive effect whereby the same is driven forcibly against the bottom of the combustion chamber of the iron, and which does not strike back from the end of the 40 burner to the gas tip, and an outer darker blue envelop flame which clings to and follows the bottom of the combustion chamber, while I show means for procuring such a ventilation of the combustion chamber as to afford a perfect 45 combustion of the fuel burned.

In the said drawings Figure 1 is a side elevation of a sad iron embodying my invention; Fig. 2 is a longitudinal mid-section view thereof; Fig. 3 is a rear view of the sad 50 iron; and Fig. 4 is a vertical cross-section view thereof on the line 4—4 in Fig. 1, looking from front to rear.

In the drawings, 1 is the body portion of the iron, having the general contour of an 55 ordinary sad iron, and preferably cast in one

piece, and having the toe 2 at its forward end. This body 1 has two side openings, which are partly closed by two metal plates, 3, 4. The plate 3 has formed on its lower side a flange 5, which projects slightly beyond the body portion of the iron. The side plate 4 on the other side of the iron has a similar flanged projection, 5, at its upper side, leaving a similar space between the said flange and the iron body. In the rear wall of the iron, I form the openings 6, 6. The spaces formed between the flanges 5, 5 and the iron body and the openings 6, 6 in the rear wall of the iron permit a sufficient ingress of air to the combustion chamber and efflux of products of combustion therefrom to insure a perfect combustion of the gas used therein. By the use of the side plates 3, 4, and their flanges, 5, I effectually screen the flame within the iron from undue drafts 75 of air and confine it well within the combustion chamber, the tortuous passages, formed between said flanges and the iron body, well effecting this end.

To heat the iron, gas is conveyed to it 80 through the gas duct 7 which is sustained by the bracket 8 formed upon the rear part of the handle 9. The gas passes through the tip 10, and thence is directed in a well defined jet through the mixing chamber 11 and the tube 85 12. Air is admitted to the mixing chamber through openings, 13, in its rear face, and the gas passing through the mixing chamber becomes partially commingled with the air before it emerges from the end of the burner tube 12. The result of this partial commingling of the gas and the air within the mixing chamber and burner tube is the production of a flame having a rather short and bright blue heat cone of remarkably vivid definition and 90 intensely calorific quality surrounded by a darker blue and more transparent envelop. This heat cone burns with a roaring, explosive and driving effect, and its end, the hottest part of the flame, impinges upon the bottom 95 100 of the combustion chamber, while the envelop flame of darker blue spreads upon said surface and flows upon it to the forward end of the combustion chamber without rolling or floating. I have illustrated this flame in Fig. 2 of the drawings, 14 being the said heat cone, and 15 being the envelop flame passing forward over the floor of the combustion chamber.

The explosive energy with which the short heat cone issues from the burner tube, its 110

immediate impingement upon the bottom of the iron, and the tenacity with which the blue envelop flame follows the surface of the bottom of the combustion chamber beyond the 5 point of impingement of the heat cone are all elements which not only aid in the efficient heating of the smoothing face of the iron, but also contribute to the prevention of any back pressure, due to rapid movements of the iron 10 itself, resulting in the striking back of the flame to the gas tip, an evil to which all atmospheric gas irons are liable. The production of such a flame enables its direction and control within the combustion chamber of the 15 iron in a manner particularly adapted to the objects in view, and without the aid of any auxiliary blowing apparatus, while, with the ventilation afforded, the combustion of the gas is perfect, no odor being produced nor soot 20 deposited.

To produce the flame described I use a peculiar and novel construction which I shall now particularly describe.

To effect the best results the burner tube 12 25 should be made short, straight and fully open at the end whence the flame issues; the mixing chamber 11 should be so constructed as to receive a liberal though not excessive supply of air, and the air should be admitted thereto 30 so as to flow as directly and evenly and with as little change of course as practicable into the burner tube. The gas tip 10 should be so located as to permit the column of gas emitted from it to be projected centrally through said 35 mixing chamber and burner tube, its axis being co-incident with the axes of those parts. I also find that by giving the interior of the gas duct an irregular conformation I procure a more forcible projection of the column of gas 40 emitted from the gas tip into the mixing chamber and burner tube than I gain by the use of a direct or regularly formed gas duct. Such additional force secured in the gas jet is of great advantage in adding to the size and 45 energy of the heat cone and aiding in overcoming any tendency of the flame to strike back to the tip.

In Fig. 2 of the drawings I have shown the gas duct, mixing chamber and burner tube of 50 the relative dimensions and conformation which I have found to produce the best results. The orifice of the gas tip is 42/1000 of an inch in diameter, the burner tube is 2 $\frac{1}{4}$ inches in length and has an internal diameter of $\frac{5}{8}$ of an inch, while the other parts of 55 the heating device and of the sad iron itself are carefully drawn to the same scale. The flow of gas to the gas tip is regulated by means of the needle valve 16, and before 60 reaching the tip the gas passing through the gas duct makes a sharp turn into the chamber 17 through which the said needle valve passes. The gas duct 7 is connected with the valve case 18 by the coupling 19, and a small chamber, 20, is formed within said

coupling, at the bottom of which chamber is a circular shoulder formed by the boss of the valve case within said coupling, such shoulder being marked 21 in the drawings. By the formation of this chamber of larger diameter than the internal diameter of the gas duct 7, I add to the force and efficiency of the gas jet passing from the tip into and through the mixing chamber and burner tube, and it is also aided by the sharp turn the gas makes 75 in its course through the chamber 17.

It will, of course, be understood that in giving the proposed proportions and dimensions of the parts mentioned, which I have found efficient in use in connection with the 80 gas pressures commonly found in our cities and towns, I do not restrict myself thereto, for the reason that I have found that the proportions, dimensions and gas pressure may be varied proportionally or otherwise so as to 85 produce the resultant cone and envelop flame by a suitable calibration of the dimensions and proportions of these parts to the pressure employed. With the same gas pressure a change in the proportionate 90 length of the burner tube results in a shortening or lengthening of the heat cone of the flame as the tube is made shorter or longer. It may be generally stated that the shorter 95 the burner tube the shorter and more explosive and energetic the heat cone, and if the burner tube be lengthened much beyond the limits hereinabove specified, and the gas be delivered under ordinary pressure, the 100 definition of the heat cone becomes much less vivid and its explosive energy is altogether lost. This result I attribute to the more thorough commingling of the gas and air passing through the burner tube. The 105 burner tube can also be made curved instead of straight, though with the same gas pressure this change of form results in a reduction of the explosive energy of the heat cone, such reduction varying with the radius of the 110 curve of the tube until entirely lost. The orifice of the gas tip may also be made larger or smaller to answer the requirements of the use to which the iron is to be put, and may 115 be varied in proportion to the size and weight of the iron, the diameter of the said orifice hereinabove specified being such as I have found useful and efficient in sad irons of the household and laundry types weighing from five to six pounds. I can also dispense with the peculiar features of the gas duct described, and omit the irregular internal conformation thereof, but with ordinary gas pressures I find it highly advantageous to use the construction of gas duct above described, the irregular internal conformation 120 of which may be varied, however, without departing from my invention.

Having thus described my invention, I claim:

1. A hollow sad iron, provided with a lon-

5. A longitudinal outlet opening extending along one of its side walls near the top thereof, for the escape of the products of combustion, and a screen extending along and in front of said opening, said screen being spaced apart from the side wall at top and closed with respect to the said side wall at bottom; substantially as described.

2. A hollow sad iron, provided with a longitudinal inlet opening extending along one of its side walls near the bottom thereof, for the inlet of air to supply combustion, and a screen extending along and in front of said opening, said screen being spaced apart from the side wall at bottom and closed with respect to the side wall at top; substantially as described.

3. A hollow sad iron, provided with a longitudinal outlet opening extending along one of its side walls near the top thereof, for the escape of the products of combustion, a screen extending along and in front of said opening, said screen being spaced apart from the side wall at top and closed with respect thereto at bottom, said sad iron being further provided with a second longitudinal opening in its other side wall near the bottom thereof, for the inlet of air to supply combustion, and a screen extending along and in front of said second opening, said latter screen being spaced apart from the side wall at bottom and closed with respect thereto at top; substantially as described.

4. A sad iron having a hollow interior, a burner tube extending within said interior, a mixing chamber connected with the burner tube, a gas jet nozzle having an interior chamber communicating with the mixing chamber, and a gas supply pipe communicating with the interior chamber of the gas jet nozzle, the end of said gas supply pipe being separated from the said interior chamber by an intervening space of larger diameter than said gas supply pipe, and the opening into the interior chamber of the gas jet nozzle being of less diameter than the gas supply pipe; substantially as described.

5. In an internally heated sad iron wherein the heating effect is obtained by means of a flame having a short light blue inner cone with a blowing and sputtering effect and an elongated outer darker envelop part, the combination with a gas duct, of a mixing chamber, an air inducing tip, and a short open ended burner tube, the open end of the burner tube being positioned in proximity to the inner face of the bottom of the iron to be heated so that the said inner cone of the flame will be directed against the said inner face of the iron, and the outer envelop part of said flame will be directed against and will follow said face.
